UNITED STATES PATENT OFFICE.

EMANUEL ROLSKY, OF KANSAS CITY, MISSOURI.

DESIGN FOR A COMBINATION REFRIGERATOR AND WALL CASE.

Application filed April 15, 1922. Serial No. 1,772. Term of patent 14 years.

To all whom it may concern:

Be it known that I, EMANUEL ROLSKY, a citizen of the United States, residing at Kansas City, in the county of Jackson and State of Missouri, have invented a new, original, and ornamental Design for Combination Refrigerator and Wall Case, of which the following is a specification, reference being had to the accompanying drawing, forming part thereof.

The figure is a perspective view of a combination refrigerator and wall case, showing my new design.

I claim:

The ornamental design for a combination refrigerator and wall case, as shown.

EMANUEL ROLSKY.
